US00D870156S

(12) **United States Design Patent** (10) **Patent No.:** **US D870,156 S**
(45) **Date of Patent:** **** Dec. 17, 2019**

(54) **POWER END FRAME SEGMENT**

(71) Applicant: **S.P.M. Flow Control, Inc.**, Fort Worth, TX (US)

(72) Inventors: **Joseph H. Byrne**, Hudson Oaks, TX (US); **Jacob A. Bayyouk**, Richardson, TX (US); **Chandu Kumar**, Fort Worth, TX (US)

(73) Assignee: **S.P.M. Flow Control, Inc.**, Fort Worth, TX (US)

(**) Term: **15 Years**

(21) Appl. No.: **29/603,989**

(22) Filed: **May 15, 2017**

Related U.S. Application Data

(63) Continuation of application No. 29/567,631, filed on Jun. 10, 2016, now Pat. No. Des. 791,193, which is a continuation of application No. 29/534,091, filed on Jul. 24, 2015, now Pat. No. Des. 759,728, which is a continuation of application No. 14/808,513, filed on Jul. 24, 2015.
